US00D952451S

(12) **United States Design Patent** (10) **Patent No.:** **US D952,451 S**
Zuk (45) **Date of Patent:** **** May 24, 2022**

(54) **FASTENER FOR ROADBED CONSTRUCTION**

(71) Applicant: **Zebulon Zuk**, Ham Lake, MN (US)

(72) Inventor: **Zebulon Zuk**, Ham Lake, MN (US)

(**) Term: **15 Years**

(21) Appl. No.: **29/684,534**

(22) Filed: **Mar. 21, 2019**

(51) LOC (13) Cl. **08-08**

(52) U.S. Cl.

USPC **D8/390**

(58) **Field of Classification Search**

(57) **CLAIM**

The ornamental design for fastener for roadbed construction, as shown and described.

DESCRIPTION

FIG. 1 is a front-right side perspective view of a fastener for roadbed construction showing my new design.

FIG. 2 is a rear-left side perspective view thereof.

FIG. 3 is a top plan view thereof.

FIG. 4 is a bottom plan view thereof.

FIG. 5 is a right side plan view thereof.

FIG. 6 is a left side plan view thereof.

FIG. 7 is a rear plan view thereof; and,

FIG. 8 is a front plan view thereof.

The broken lines in the figures are for illustrative purposes only and form no portion of the claimed design.

1 Claim, 4 Drawing Sheets
